UNITED STATES PATENT OFFICE.

JOSEPH F. STANLEY, OF MINNEAPOLIS, MINNESOTA.

BED BRACE.

Application filed January 6, 1923. Serial No. 611,032.

To all whom it may concern:

Be it known that I, JOSEPH F. STANLEY, a citizen of the United States, residing at Minneapolis, in the county of Hennepin and 5 State of Minnesota, have invented certain new and useful Improvements in Bed Braces, of which the following is a specification, reference being had to the accompanying drawings.

10 This invention relates to certain improvements in bed braces and it is an object of the invention to provide a novel and improved device of this general character which, when in applied position, serves to 15 materially strengthen the bed structure and to stiffen up the same irrespective of the looseness in the joints of the bed structure and thereby making the bed structure rigid.

Furthermore it is an object of the invention 20 to provide a novel and improved device of this general character which is capable of applying equal tension at the four corners of the bed structure.

The invention consists in the details of 25 construction and in the combination and arrangement of the several parts of my improved bed brace whereby certain important advantages are attained and the device rendered simpler, less expensive and otherwise 30 more convenient and advantageous for use, as will be hereinafter more fully set forth.

The novel features of my invention will 35 hereinafter be definitely claimed.

35 In order that my invention may be the better understood, I will now proceed to describe the same with reference to the accompanying drawings, wherein:

Figure 1 is a view in top plan of the bed 40 brace constructed in accordance with an embodiment of my invention and in applied position;

Figure 2 is an enlarged fragmentary view 45 of the brace as herein disclosed;

Figure 3 is a view partly in plan and partly in section of the structure as illustrated in Figure 2; and

Figure 4 is an enlarged fragmentary view 50 partly in section and partly in elevation illustrating the means for connecting the flexible member with a bed post or corner.

As disclosed in the accompanying drawings, B denotes a bed structure embodying corner posts 1. My improved brace as herein 55 disclosed comprises a pair of oppositely disposed U-shaped members or brackets 2

having in threaded engagement with their base portions the interposed shank 3. The opposite end portions of the shank 3 are reversely threaded so that upon requisite rotation of the shank 3 the members or brackets 2 will be caused to move one toward or from the other. The central portion of the shank 3 is provided with an operating handle 4 whereby the requisite rotation may be imparted thereto.

Rotatably supported between the side arms of each of the members or brackets 2 is a flanged roller 5 over which passes a flexible band 6 preferably of metal. The 70 extremities of the band 6 are secured to the corner posts 1 preferably at a point below but in relatively close proximity to the rails 7.

While any desired means may be employed for attaching the band 6 to the posts 1 I find it preferable to employ the arrangement particularly illustrated in Figure 4 wherein the band 6 is directed through an annular member or ring 8 and then 80 around the posts 1 and then back over the bar of the member 8 and around the posts 1 and then disposed through the member or ring 8 and then bent inwardly. By this arrangement upon pull being imposed upon the band 6 the resultant loops 9 coacting with the posts 1 will be tightened effecting the desired securing of the band 6 with the posts 1.

90 After the band 6 has been properly connected the shank 3 is rotated to move the members or brackets 2 inwardly one toward the other resulting in strain being imposed upon the band 6, the pulleys 5 assuring the proper centering of the members or brackets 2 with respect to the band 6. The tightening of the band 6 will assure the maintenance of the bed structure rigid and in the event the bed is out of square the brace will bring the structure back perfectly square. With 95 the use of my improved device the strain is at all times equally divided irrespective of the manner or direction in which the bed structure may be moved.

100 From the foregoing description it is thought to be obvious that a bed brace constructed in accordance with my invention is particularly well adapted for use by reason of the convenience and facility with which it may be assembled and operated, and it 110 will also be obvious that my invention is susceptible of some change and modification

without departing from the principles and spirit thereof and for this reason I do not wish to be understood as limiting myself to the precise arrangement and formation of the several parts herein shown in carrying out my invention in practice except as hereinafter claimed.

I claim:

In combination with the supporting posts of an article of furniture, a flexible metallic member arranged at each side of the article, a ring coacting with the end portion of the

flexible member, said flexible member being directed through the ring and around the adjacent post and then returned over the bar of the ring and around the post and again through the ring and then extending outwardly, and means coacting with the central portions of the flexible members for placing the same under tension.

In testimony whereof I hereunto affix my signature.

JOSEPH F. STANLEY.
